UNITED STATES PATENT OFFICE.

BENONI COLVIN, OF FREEPORT, ILLINOIS, ASSIGNOR, BY MESNE ASSIGNMENTS, TO THE LUCE SPRING HINGE COMPANY, OF PORT WASHINGTON, WISCONSIN.

SPRING-HINGE.

SPECIFICATION forming part of Letters Patent No. 361,989, dated April 26, 1887.
Application filed August 19, 1886. Serial No. 211,268. (Model.)

To all whom it may concern:

Be it known that I, BENONI COLVIN, a citizen of the United States, residing at Freeport, in the county of Stephenson and State of Illinois, have invented certain new and useful Improvements in Spring-Hinges for Doors, of which the following is a specification.

The object of this invention is to produce double-action adjustable spring-hinges which combine the advantages of simplicity of construction, durability, and great strength.

This invention consists in so constructing spring-hinges that they will hold a door either open or closed, according as desired, and that admit of having their opening and closing force easily and quickly regulated.

In the accompanying drawings, which form a part of this specification, Figure 1 is a view of a front elevation of my improved hinge in position to hold a door closed. Fig. 2 is a view of a rear elevation of the same hinge in position to hold a door open. Figs. 3 and 4 are top end views of Figs. 1 and 2, respectively. Figs. 5, 6, 7, 8, 9, and 10 are isometrical views of various parts of the hinge. Figs. 11 and 12 are views in detail of parts of the same.

Like letters of reference indicate corresponding parts throughout the several views.

A represents a view of a hinge-plate provided with the hooks A' and ears A² A³, the former ear supporting the cylindrical pintle A⁴, the latter ear having the semi-cylindrical slot A⁵.

B represents a view of a counterpart hinge-plate, provided with the hooks B' and ears B² B³, the former ear being pierced by the circular opening B⁴, which should be of proper diameter to readily admit the pintle A⁴, and the latter ear having the semi-cylindrical slot B⁵, which should be of the same dimensions as the slot A⁵.

C represents a hinge-leaf provided with the eyes C', for receiving the hooks A' of the hinge-plate A.

C² C³ represent ears, the former provided with the vertical slot c and boss c', the circular opening C⁴ extending entirely through the parts c' C³, the latter having the circular opening C⁵.

D represents a counterpart hinge-leaf provided with the eyes D', for receiving the hooks B' of the hinge-plate B, and detent d, for locking a part to be hereinafter described.

D² D³ represent ears, the former provided with the pintle D⁴, of proper diameter to readily enter the lower end of the circular opening C⁴ of the ear C³, the latter having the circular opening D⁵.

E represents a pintle-key furnished with a thumb-piece, E', having the pintle portion E² cylindrical in form and the key portion E³ squared, or of any other suitable shape.

F represents a circular spring-cap having a portion of its periphery indented with notches F', and provided with the slot F² and boss F³.

A rectangular opening, F⁴, of sufficient size to admit the key E³ of the pintle-key E and boss F³.

To put the parts of the hinge together, insert the pintle D⁴ into the lower end of the opening C⁴ of the ear C³, putting the ear D³ of the hinge-leaf D immediately below the ear C³ of the hinge-leaf C, bring the edges x of hinge-leaves C D together, pass the hooks A' of the hinge-plate A through the eyes C' of the hinge-leaf C, insert the pintle A⁴ into the opening B⁴ of the ear B³, and insert the hooks B' of the hinge-plate B through the eyes D' of the hinge-leaf D, placing the ear B³ of the hinge-plate B immediately above and upon the ear A³ of the hinge-plate A. Next open the hinge-plates A B, and they, together with the hinge-leaves C D, will assume the positions shown in Figs. 1 and 3. Then place the part G' of the spiral spring G into the slot F² of the spring-cap F, place the part G² of said spring into the slot c in the ear C³ of the hinge-leaf C, and press the spring-cap F below the ear D³, letting the detent d of the spring-leaf D drop into a notch, F', of said spring-cap. When the parts have been arranged as indicated, the axes of the circular openings A⁵, B⁵, C⁵, and D⁵ through the ears A³, B³, C³, and D³, respectively, and the middle joint of the rectangular opening F⁴ through the spring-cap F, will lie in one and the same straight line. Insert the pintle-key through the last-named openings and the spiral spring G, letting the

end of the key enter the opening C⁴ in the boss c'.

To tighten the spring G, press on the top of the pintle-key E until the spring-cap F is released from the detent d, turn the pintle-key to the left, and let another notch F' of the spring-cap engage the detent d.

The hooks A' B' of the hinge-plates A B form, with the eyes C' D' of the hinge-leaves C D, secondary hinges, which allow the hinge-leaves C D and the spring G, inclosed between them, and the hinge-cap F and pintle-key E, to swing inward or outward, according as the door is closed or opened, as shown in Figs. 3 15 and 4, respectively.

The result of the outward and inward motions of the parts C, D, E, F, and G is to carry the dead-point of the hinge outward or inward far enough to reverse the action of the spring G.

20 Accordingly, every time a door to which this spring is attached is opened wide or partially closed the action of the spring G is reversed and holds the door either open or closed, according to the position in which it 25 is left by the operator.

I claim—

2 In a double-action adjustable spring hinge,

the combination, with the hinge-plate A, having the hooks A' and ears A² A³, the former provided with the pintle A⁴ and the latter 30 cleft by the slot A⁵, of the hinge-plate B, having the hooks B' and ears B² B³, the former provided with the circular opening B⁴, the latter cleft by the slot B⁵, the hinge-leaf C, having the eyes C' and ears C² C³, the former 35 provided with the slot c and boss c', which, with the ear C², is perforated by the circular opening C⁴, the latter ear also being perforated by the circular opening C⁵, the hinge-leaf D, having the detent d and ears D² D³, the former provided with the pintle D⁴, the latter 40 perforated by the circular opening D⁵, the pintle-key E, the spring-cap F, provided with the notches F', the slot F², and central rectangular opening, F⁴, and the spiral spring G, 45 substantially as described, and for the purpose specified.

In testimony whereof I affix my signature in the presence of two witnesses.

BENONI COLVIN.
